UNITED STATES PATENT OFFICE.

GEORGE A. SCOTT, OF NEW YORK, N. Y.

DESIGN FOR A BACK OF A BRUSH.

SPECIFICATION forming part of Design No. 12,797, dated February 28, 1882.

Application filed January 10, 1882. Term of patent 14 years.

To all whom it may concern:

Be it known that I, GEORGE A. SCOTT, a citizen of the United States, residing in the city of New York, State of New York, have 5 invented and produced a new and original Design for the Backs of Brushes, of which the following is a specification.

This invention relates to a design for the backs of brushes; and it consists in the ornamental configurations hereinafter described and illustrated in the annexed drawings, in which—

Figure 1 represents the back of a hair-brush provided with a handle and ornamented in accordance with my invention. Fig. 2 represents the back of a flesh-brush ornamented in a similar manner.

The back of the brush is mainly divided into three separate spaces, A, B, and C, by means 20 of lines which are arranged to form ornamental borders for said spaces, as will be presently more particularly described. Within the space A, which is at one end of the back of the brush, is arranged a human arm, *a*, clothed 25 in armor, the hand of this arm being represented as grasping a number of flashes, *b*, of lightning, and a portion of the arm being surrounded by representations of electric coruscations *c*. The portion *a*² of the border for this 30 space is composed of two lines substantially concentric with the margin of the brush-back. These lines terminate in scrolls *b*², which are located adjacent to the ends of a pair of curved lines, *c*², that cross the brush-back transversely 35 to its length and form a portion of the border for the space containing the arm just described. These transverse lines are enveloped by a coil, *d*, for a portion of their length, the mailed arm and its surrounding coruscations being represented as projecting from said coil. The 40 space B at the other end of the brush-back is bounded by a border comprising various representations of scroll-work. Thus that portion of the border *e* which crosses the brush-back, and which is concentric with the part *c*² of the 45 border belonging to the space just described, comprises a plane curved outer line and an inner line diverging at intervals to form small scrolls within the space B. The portion *c*³ of the border for this space, which runs substantially parallel or concentric with the side edges 50 of the brush-back, is divided into the inter-

twining scroll-like figures *f* and the two long tapering and wavy strips or leaves *g* emanating from scrolls *h*, which, in conjunction with 55 a scroll, *i*, arranged intermediate of these two scrolls, afford spaces for an appropriate motto or inscription. Within the space B is a belt, *k*, arranged to form a circle, and having its ends secured by a buckle. The circular space 60 inclosed by this belt is divided into four sectors bearing the figures emblematic of the British coat of arms, the figure formed by said belt being surmounted by the royal crown. The space C, that is respectively bounded on 65 two sides by the boundary-lines *c*² and *e* of the spaces A and B, is in the nature of a segment, opening at both ends into the marginal space *l*, which is upon the brush-back between its rim and the lines which bound the spaces A 70 and B. This space C is utilized for a name or symbol. These spaces A, B, and C are fretted, as hereinafter represented, which adds to the general ornamental effect.

In the brush shown in Fig. 1, in which a 75 handle is provided, the back of said handle is ornamented in the following manner: At a point at or near the center of the back of the handle is arranged an oval shaped figure, *M*, with a diagonal bend or band, *m*. This figure 80 is encircled by a scalloped border, *m*², having small spherical figures upon the points between its scallops. A raised rib or a bar, *n*, running longitudinally the length of the handle, is represented as extending from one end 85 of this last-described figure, and an ornamental scroll, *p*, partaking somewhat of the character of the letters S and C combined, is shown twined about said rib. At that end of the rib which is opposite to the end joining the figure 90 having an escalloped border is a T-shaped figure, *Q*, comprising a diamond-shaped figure, *q*, intersected by said rod and crossed by a short rod or rib, from the ends of which depend two tassels, *r* *r*. At the opposite end of 95 the oval-shaped figure having an escalloped border is arranged an ornamentation, *S*, comprising two pyramidal-shaped figures, *t*, each having at its base a small pyramidal-shaped figure, the apices of said small pyramids being arranged to meet. From between these 100 double pyramidal-shaped figures branch out the four scrolls *v* *v* *v* *v*'. These scrolls extend in pairs toward opposite ends of the handle, so

as to embrace the pyramidal-shaped figures, as shown.

What I claim is—

1. A design for a brush-back, consisting in the representation of a mailed human arm grasping electric flashes in its hand and arranged within a space inclosed by an ornamental border, substantially as described.
2. In a design for a brush-back, a belt buckled at its ends and arranged to form a circle, with the representation of armorial bearings within the space inclosed by the belt and a crown surmounting the figure formed thereby, the whole being arranged within a space surrounded by an ornamental border, substantially as described.
3. In a design for a brush-back, the segmental-shaped space C, bordered on two sides by the ornamental lines c^2 and e, substantially as described.

4. In a design for a brush-back, the oval-shaped figure M, diagonally crossed by a band and surrounded by an escaloed border, substantially as described.

5. In a design for a brush-back, the scroll p, ²⁵ substantially representing the letters S and C combined and twined about a rod, and the diamond-shaped figure at the end of the said rod crossed by a short rod having tassels depending from its end, substantially as described.

In testimony whereof I have hereunto set my hand in the presence of two subscribing witnesses.

GEO. A. SCOTT.
